(57) **CLAIM**

The ornamental design for a lighted cable termination assembly, as shown and described.

DESCRIPTION

FIG. 1 is an isometric view of a front, top, and left side of a lens for a lighted cable termination assembly;

FIG. 2 is a left side elevational view of the lens of FIG. 1;

FIG. 3 is a right side elevational view of the lens of FIG. 1;

FIG. 4 is a front elevational view of the lens of FIG. 1;

FIG. 5 is a rear elevational view of the lens of FIG. 1;

FIG. 6 is a top plan view of the lens of FIG. 1; and,

FIG. 7 is a bottom plan view of the lens of FIG. 1.

The broken lines showing a portion of the lighted cable termination assembly form no part of the claimed design. The lens depicted in FIGS. 1-7 is transparent or translucent.

1 Claim, 6 Drawing Sheets
